APPARATUS FOR DISPENSING GAS MATERIAL

Wilfried Haumann, Kenmore, N.Y., assignor to Union Carbide Corporation, a corporation of New York

Application March 25, 1957; Serial No. 648,395

11 Claims. (Cl. 62—51)

This invention relates to a method of and apparatus for storing and dispensing low-boiling liquefied gases; low-boiling gases may be defined as those having boiling points at atmospheric pressure below 230° F., such as oxygen and nitrogen, for example. More particularly, it concerns an improved method and apparatus for delivering such materials in gaseous form from liquid storage, ready for immediate use at superatmospheric pressure.

Insulated converters are commonly employed for receiving a low-temperature liquefied gas and vaporizing and dispensing the gas at a controlled superatmospheric pressure. These converters must also serve as highly effective storage vessels to conserve the liquefied gas during extended periods of time in which there may be no dispensing of the contents. Since the liquid charged into these converters is normally saturated (in thermal equilibrium with its vapor) with respect to a low delivery pressure, special provisions are needed to impose and maintain a higher nonequilibrium pressure sufficient for the needs of the consuming system. Some prior converters have withdrawn liquid from a lower region of the container under the gravity head of liquid within the container in order that a pressure building vaporizer may receive liquid by gravity flow regardless of the pressure existent in the vessel. Pressure building must then be controlled by a valve usually located in the vapor return circuit to the vessel. Unless the valve employed for this purpose is leak-tight, the pressure building system cannot be completely inactivated due to the constant driving force applied by the stored liquid in the container. If valve leakage occurs in such converters and the consuming system is idle for an appreciable period of time, excessive pressures will be generated as a result of the incomplete dead-ending of the pressure builder.

Other earlier converters have employed a small external pressure building chamber separate from and above the converter container and have thereby eliminated the constantly applied driving force of the stored liquid. Such chambers were fed by the over-top withdrawal of liquid from the converter under a pressure differential created by venting gas from the chamber (either continuously or intermittently) to the atmosphere. Such venting of gas is wasteful and expensive and precludes making an accurate accounting of the material stored and dispensed. The arrangement is not a positive solution to the problem since the valve which is required for controlling the chamber vent may leak and thereby permit continuous and unwanted pressure building.

Furthermore, prior converters have usually employed at least one other control valve, and often two, for the proper regulation of the additional withdrawal of both liquid and gas from the vessel for delivery to the consumer.

In accordance with this invention, the pressure building means can be positively inactivated without depend-

ence upon the leak-tightness of a control valve. Also, complete control of both pressure building and consumer withdrawal can be accomplished in this system by only a single automatic control.

It is therefore the principal object of this invention to provide a system for storing and dispensing liquefied gases which employs simplified and more dependable automatic controls, and permits the consumer to withdraw material from the container with a minimum amount of attentiveness and skill on his part.

A more particular object of the invention is to provide a converter for storing low-boiling materials in liquefied form and for dispensing such materials in gaseous form, which is provided with an automatic pressure building and vaporizing system.

These and other objects, features, and advantages of the present invention will become apparent from the following detailed description of the accompanying drawings in which:

Fig. 1 is a vertical transverse section through a container embodying the system of the present invention; and

Fig. 2 is a fragmentary vertical section of a container similar to that shown in Fig. 1, but illustrating a modified form of gas withdrawal system.

As shown in the drawings, a customer container or converter 16 provides a unique system for dispensing in gaseous form and at a predetermined service pressure material stored in liquid phase. Customer service is inaugurated simply by connecting service line 60 to the customer's line (not shown), said customer's line usually having a pressure regulating valve therein. The service line 60 is connected through a vaporizing coil 64 disposed between the converter casing 17 and an inner vessel 18 with both the liquid and gas phases of the vessel 18. The liquid phase connection, an eduction tube 66, passes from a point near the bottom of the vessel 18 upwardly to a loop 68 where it is reversely bent to extend downwardly to a line 70 which leads radially outwardly to a T-junction 72 interconnecting the liquid withdrawal line, the gas withdrawal line 74 and a line 76 leading to the inlet end of the vaporizing coil 64. The gas withdrawal line 74 is connected with the gas phase of the vessel through a back pressure controller, or gas flow regulator 78, which is preferably disposed in the head 80 of the converter 16. Regulator 78 includes a chamber 81 which is open to the gas space of the vessel 18 through a passageway 82 and has a valve plunger 84 which is connected with a bellows 86 and which is normally urged toward a closed position by a compression spring 88 acting on one side of the bellows. The other side of the bellows is subject to pressure in the gas space which opposes the spring and will act to lift the plunger 84 when vessel pressure exceeds the setting of the regulator, thereby opening the gas space to the service connection 60 through the regulator 78, lines 74 and 76 and the coil 64. Thus, whenever pressure in the vessel 18 exceeds the setting of the regulator because of evaporation due to heat leak, the regulator opens and remains open until the pressure falls below such setting. If vessel pressure is above the setting at the initiation of a withdrawal period or becomes so during withdrawal period, withdrawal automatically takes place from the gas phase of the vessel until pressure in the vessel falls slightly below the setting of regulator 78.

Line 76 leading to the coil 64 is branched about at the normal full liquid level at another T-junction or interconnection 90. A line 92 extends from this point vertically downward to a check valve 94 at one end of a vaporizing coil 96 forming part of a means for building and maintaining a pressure in the vessel 18 at a substantially constant value during withdrawal for effecting

delivery of the liquid phase material to the vaporizing coil 64 for delivery to the service connection 60 at the desired substantially constant pressure. The inlet portion of vaporizer coil 96 is located below the level of the liquid in the vessel 18, and preferably below the lowest point on the bottom of vessel 18 as shown in Figure 1. A vapor return line 98 leads from the other end of coil 96 to the top part of vessel 18 for delivery of vaporized material into the gas space for building a non-equilibrium pressure therein.

Operation of the pressure building system is automatic, and gas will be generated for pressure building whenever liquid is available in line 92. A unidirectional flow device such as check valve 94 acts to prevent back-flow of vapor from the vessel gas space to the customer through the pressure building circuit and to prevent the vapor generated in the pressure building coil from flowing back to the customer rather than to the gas space of the vessel. As an alternative to the check valve, line 92 may be extended in the form of an elongated liquid trap attached directly to, and in good thermal communication with, the outer wall of the container. The upwardly extending legs of such a trap would continue above the normal full liquid level with one leg being attached to connection 90, and the other returning downwardly to pressure builder 96. Through an unobstructed line of this configuration, liquid may flow freely from connection 90 to the pressure building vaporizer, but vapor cannot normally return through the line to connection 90 due to the liquid seal maintained in the trap.

When a customer desires to make a withdrawal, the opening of the service connection to a demand establishes a pressure differential between line 60 and the interior of the vessel 18. If the pressure in the gas space exceeds the setting of regulator 78, withdrawal takes place from the gas phase as described above. If vessel pressure is below the setting of the regulator, the established pressure differential causes liquid to be forced up through the eduction line 66, over loop 68, down through lines 70 and 76, and into the vaporizer coil 64. At the same time, the flow of liquid into line 76 also results in the filling of vertical line 92 between interconnection 90 and check valve 94. The head thus established in line 92 provides a driving force for operating the pressure building system (i.e. liquid flows under the force of this head into the coil 94, is vaporized and returns as gas through line 98 to the gas space of the container).

As shown in Fig. 2, the head in the line 96a may be employed to feed liquid to the coil 96. In such a case, an interconnection 90a is provided at the lower end of the vertical line to pass liquid in such line to both the vaporizing coil 64 and to the pressure building vaporizing coil 96 through check valve 94. This however could require a larger line to accommodate both the vaporizer and pressure building coil liquid flows. The larger line would hold more liquid which must, at the termination of a liquid withdrawal period, drain through the pressure building coil 96, thereby resulting in a less desirable, larger pressure override in the vessel 18.

If container pressure reaches the setting of the regulator 78 during liquid withdrawal, valve 84 opens. When this valve opens, the pressure drop between interconnection 72 and the gas space is lower than the pressure drop across lines 66, 68 and 70, liquid flow is terminated, and further withdrawal takes place from the gas phase. Since liquid is no longer available at the interconnection 90 for delivery into line 92, the pressure building system automatically ceases to function until the pressure in the vessel falls below the setting of the regulator 78 to effect closing of valve 84. In order to insure against continued withdrawal of liquid when valve 84 opens, the junction point 72 must be at a level near or preferably above the normal full liquid level of the container so that any siphon action that might otherwise

cause continued liquid flow will be destroyed. The loop 68 extends above the normal full liquid level of the container so as to provide and serve as a gas trap in the event the container is overfilled. Thus, if the container is overfilled, residual liquid in the coil 64 at the termination of a withdrawal vaporizes and expands, or residual gas in the coil 64 expands, and the gas under pressure forces liquid in the down side of the loop 68 back up over the top of the loop and forms a gas trap to prevent liquid feeding into the relatively warm vaporizing coils 64 and 96. Otherwise, if the top of the eduction tube were below the liquid level in an overfilled condition, liquid would feed into the warm coils and force warm gas back into the container, thereby adding undesired heat to the container.

It will be noted that liquid flows from container 18 only through a withdrawal line extending upwardly from the bottom of the vessel to a height above the normal full liquid level. A conduit, gravity-fed with liquid from the withdrawal line, is connected outside the inner vessel to the inlet of pressure builder 96. Thus, the driving force or the liquid head exerted by gravity on the pressure builder is only that liquid in the downwardly extending portions of the withdrawal line and feed conduit, and this liquid head can be applied or completely removed at will by a single control valve.

The overtop withdrawal of subcooled liquid for both pressure building and dispensing purposes in this unique manner is critically dependent upon the maintenance of non-equilibrium pressure in container 18 at all times. We have discovered that non-equilibrium pressure can be maintained in stationary converters without pressure building over indefinite periods of idle storage. During filling operations, proper precaution must be taken to avoid excessive condensation of pressurizing vapor in the colder liquid entering the container. A suitable method of manually controlling the pressure during filling is described in U.S. Patent 2,368,215 to O. A. Hansen. Alternatively, automatic pressure control while filling the converter may be obtained as shown in Figure 1 by means of a filling line 99a provided along its length inside the container with small holes or slits 99. The holes or slits are properly sized and distributed in order to proportion the flow of liquid between gas phase and liquid phase entry in such manner that the container pressure remains reasonably steady.

By means of the dispensing arrangement which has been described herein, a relatively simple and automatic converter is obtained which has a minimum number of moving parts, providing reliability and greater dependability, and which allows the customer to withdraw gas at will without attention to, or control of, the converter.

It should be apparent however that various details of construction can be changed without departing from the spirit of this invention as defined in the appended claims.

55 What is claimed is:

1. Apparatus for dispensing in gaseous form a low-boiling gas material stored in liquefied form, comprising a heat-insulated container for holding such liquefied gas material under a predetermined superatmospheric pressure; a service connection for consumption apparatus having a vaporizer therein; a liquid withdrawal line extending upwardly from one end at a lower region of the container to above normal full liquid level of the container and being connected at its other end to said service connection, said liquid withdrawal line being open to provide a free flow passageway between the lower region of the container and the service connection so that liquid can pass freely through said withdrawal line to said service connection whenever a pressure difference exists across the liquid withdrawal line that is at least equal to the flow resistance therein; a gas phase withdrawal line connecting the upper region of the container above the normal full liquid level with the liquid withdrawal line at a point above said level; valve means in said gas phase

line being normally closed but responsive to container pressure so as to open the top region of the container to the service connection when the pressure in said container rises to a desired value above said predetermined pressure and cause material to be withdrawn in gas phase from the top region of the container; and pressure building means for maintaining pressure in said container comprising an external fluid circuit having a feed line connected at one end with the liquid withdrawal line at a point such that liquid from the withdrawal line flows into the feed line by gravity, a vaporizer connected with the other end of said feed line and positioned to receive liquid therefrom under gravity, and a return line for passing vaporized material from the vaporizer to the container above the normal full liquid level.

2. Apparatus as defined in claim 1, including unidirectional flow means in said external fluid circuit positioned to permit fluid flow in a direction from the liquid withdrawal line to the vaporizer but restricting fluid flow in a direction from the upper region of the container to the liquid withdrawal line.

3. Apparatus for dispensing in gaseous form a low-boiling gas material stored in liquefied form, comprising a heat-insulated container for holding such liquefied gas material under a predetermined superatmospheric pressure; a service connection for consumption apparatus having a vaporizer therein; a liquid withdrawal line extending upwardly from one end at a lower region of the container to above the normal full liquid level of the container and being connected at its other end to said service connection, said liquid withdrawal line being open to provide a free flow passageway between the lower region of the container and the service connection so that liquid can pass freely through said withdrawal line to said service connection whenever a pressure difference exists across the liquid withdrawal line that is at least equal to flow resistance therein; a gas phase withdrawal line connecting the upper region of the container above the normal full liquid level with the liquid withdrawal line at a point above said level; valve means in said gas phase line being normally closed but responsive to container pressure so as to open the top region of the container to the service connection when the pressure in said container rises to a desired value above said predetermined pressure and thereby terminate liquid withdrawal from the lower region of the container and initiate gas withdrawal from the top region of the container; and pressure building means for maintaining pressure in said container comprising an external fluid circuit having a feed line connected at one end with the liquid withdrawal line at a point such that liquid from the withdrawal line flows into the feed line by gravity, a vaporizer connected with the other end of the feed line and positioned to receive liquid from said feed line under a total gravity head of liquid at least equal to the height of liquid in said container, and a return line for passing vaporized material from such vaporizer to the container above the normal full liquid level; said external fluid circuit containing therein unidirectional flow means positioned to permit fluid flow in a direction from the liquid withdrawal line to the vaporizer but restricting fluid flow in a direction from the upper region of the container to the liquid withdrawal line.

4. Apparatus for dispensing in gaseous form a low-boiling gas material stored in liquefied form, comprising a heat-insulated container for holding such liquefied gas material under a predetermined superatmospheric pressure; a service connection for consumption apparatus having a vaporizer therein; a liquid withdrawal line having a first, upwardly extending leg leading from a lower region of the container to above the normal full liquid level of the container and a second leg extending downwardly to a lower region of the container and being connected at its lower end with said service connection; said liquid withdrawal line being open to provide a free flow

passageway between the lower region of the container and the service connection so that liquid can pass freely through said withdrawal line to the service connection whenever a pressure difference exists across the liquid withdrawal line that is at least equal to flow resistance therein; a gas phase withdrawal line connecting the upper region of the container above the normal full liquid level with the liquid withdrawal line at a point above said level; valve means in said gas line being normally closed but responsive to container pressure so as to open the top region of the container to the service connection when the pressure in said container rises to a desired value above said predetermined pressure and cause material to be withdrawn in vapor phase from the top region of the container; and pressure building means for maintaining pressure in said container comprising an external fluid circuit having a feed line connected at one end with the liquid withdrawal line at a point such that liquid from the withdrawal line flows into the feed line by gravity, a vaporizer connected with the other end of said feed line and disposed at a lower region of the container to receive liquid therefrom under gravity flow, and a return line for passing vaporized material in such vaporizer to the container above the normal full liquid level.

5. Apparatus as defined in claim 4, wherein said feed line is connected with said liquid withdrawal line at about the normal full liquid level so as to establish a relatively constant head on the pressure building vaporizer throughout the withdrawal period.

6. Apparatus as defined in claim 4, wherein said feed line is connected with said downwardly extending leg of the liquid withdrawal line in the vicinity of the lower end thereof so as to utilize the liquid head in said downwardly extending leg to serve as the driving force for the pressure building circuit.

7. Apparatus for dispensing in gaseous form a low-boiling gas material stored in liquefied form, comprising a heat-insulated container for holding such liquefied gas material under a predetermined superatmospheric pressure; a service connection for consumption apparatus having a vaporizer therein; a liquid withdrawal line extending from one end at a lower region of the container upwardly to above the normal full liquid level of the container and being provided with a reversely bent loop, the bight of which lies at a level near the top of the container; said liquid withdrawal line also having a portion leading from the other end of the loop to said service connection, said liquid withdrawal line being open to provide a free flow passageway between the lower region of the container and the service connection so that liquid can pass freely through said withdrawal line to said service connection whenever a pressure difference exists across the liquid withdrawal line that is at least equal to flow resistance therein; a gas phase withdrawal line connecting the upper region of the container above the normal full liquid level with the liquid withdrawal line at a point above said level; valve means in said gas phase line being normally closed but responsive to container pressure so as to open the top region of the container to the service connection when the pressure in said container rises to a desired value above said predetermined pressure and cause material to be withdrawn in gas phase from the top region of the container; and pressure building means for maintaining pressure in said container comprising an external fluid circuit having a feed line connected at one end with the liquid withdrawal line at a point such that liquid from the withdrawal line flows into the feed line by gravity, a vaporizer connected with the other end of said feed line and positioned to receive liquid therefrom under gravity, and a return line for passing vaporized material from the vaporizer to the container above the normal full liquid level.

55 8. A process for converting a low boiling liquefied gas to gaseous form and for delivering gas at a predetermined elevated pressure to a withdrawal connection in response

to a demand for gaseous material, comprising providing an insulated container under said predetermined elevated pressure with liquid saturated with respect to a pressure substantially lower than said predetermined pressure, conducting liquid from a lower region of the container to an upper region above the normal full liquid level in the container under a pressure differential established between the existing container pressure and the pressure in the withdrawal connection when the latter is opened to supply a demand for said material, vaporizing said liquid for delivery to consuming means, conducting additional liquid under said pressure differential from a lower region of the container to an upper region above the normal full liquid level in the container, further conducting said additional liquid downwardly by gravity flow through a height at least equal to the height of liquid in said container, vaporizing said additional liquid and passing the vaporized additional liquid to the upper region of said container above the normal full liquid level to maintain non-equilibrium conditions in the container at said predetermined pressure; and at container pressures exceeding said predetermined pressure, opening the upper region of the container to the withdrawal connection at a point above the normal full liquid level therein so that said pressure differential between said container pressure and the pressure in the withdrawal connection is reduced to a value below that required for said conductings of liquid and additional liquid, thereby terminating said conductings of liquid and additional liquid and initiating the flow of gas from said upper region to the withdrawal connection.

9. A method of delivering low boiling gas material at a predetermined pressure from a source in which said material is stored both in liquid phase and in gas phase, said liquid phase being under the pressure of the gas phase and saturated with respect to a pressure substantially lower than the pressure of said gas phase, conducting liquid from the liquid phase upwardly against the force of gravity to a height at least above the normal full liquid level of said source under a pressure differential created between the pressure in the gas phase and the pressure in a withdrawal line by the existence of a demand for stored material, said pressure differential being sufficient to overcome said force of gravity acting on said liquid, passing at least part of the liquid at such height into said withdrawal line to meet said demand, utilizing the added potential energy of the liquid at such height to drive some of such liquid through a pressure building circuit and to return vapor formed therein to said gas phase to increase the pressure thereof, and when the pressure of said gas phase exceeds said predetermined pressure by a preselected amount, releasing vapor from said gas phase into the withdrawal line to control the pressure of the gas phase.

10. A method of delivering low boiling gas material at a predetermined pressure from a source in which said material is stored both in liquid phase and in gas phase, said liquid phase being under the pressure of the gas phase and saturated with respect to a pressure substantially lower than the pressure of said gas phase, conducting

liquid from the liquid phase upwardly against the force of gravity to a height at least above the normal full liquid level of said source under a pressure differential created between the pressure in the gas phase and the pressure in a withdrawal line by the existence of a demand for stored material, said pressure differential being sufficient to overcome said force of gravity acting on said liquid, passing at least part of the liquid at such height into said withdrawal line to meet said demand, utilizing the added potential energy of the liquid at such height to drive some of such liquid through a pressure building circuit and to return vapor formed therein to said gas phase to increase the pressure thereof, and when the pressure of the gas phase exceeds said predetermined pressure by a preselected amount, releasing gas from said gas phase into said withdrawal line at a point above the normal full liquid level of said source, thereby terminating the upward conduction of liquid and preferentially delivering gas from the gas phase to said withdrawal line.

11. Apparatus for dispensing a gaseous form a low-boiling gas material stored in liquefied form, comprising a heat-insulated container for holding such liquefied gas material under a predetermined superatmospheric pressure; a service connection for consumption apparatus having a vaporizer therein; a liquid withdrawal line extending upwardly from one end at a lower region of the container to above normal full liquid level of the container and being connected at its other end to said service connection, said liquid withdrawal line being open to provide a free flow passageway between the lower region of the container and the service connection so that liquid can pass freely through said withdrawal line to said service connection whenever a pressure difference exists across the liquid withdrawal line that is at least equal to the flow resistance therein; a gas phase withdrawal line connecting the upper region of the container above the normal full liquid level with the liquid withdrawal line; valve means in said gas phase line being normally closed but responsive to container pressure so as to open the top region of the container to the service connection when the pressure in said container rises to a desired value above said predetermined pressure and cause material to be withdrawn in gas phase from the top region of the container; and pressure building means for maintaining pressure in said container comprising an external fluid circuit having a feed line connected at one end with the liquid withdrawal line at a point such that liquid from the withdrawal line flows into the feed line by gravity, a vaporizer connected with the other end of said feed line and positioned to receive liquid therefrom under gravity, and a return line for passing vaporized material from the vaporizer to the container above the normal full liquid level.
